JAMES EDWARD BRATT AND CHARLES HUNTER BOYD, OF SYRACUSE, NEW YORK, AS
SIGNORS TO CONTINENTAL CAN COMPANY, INC., OF NEW YORK, N. Y., A CORPORA-
TION OF NEW YORK

MECHANISM FOR NOTCHING AND FEEDING BODY BLANKS TO BODY MAKERS

Application filed February 2, 1928. Serial No. 251,279.

The invention relates to new and useful improvements in a mechanism for notching and feeding body blanks to a body maker, and more particularly to a body maker for forming and completing cylindrical can bodies. It is a common expedient to feed body blanks from a magazine to the forming rolls of body makers, so that the body blank is rolled into a cylindrical body. It is also a common expedient to notch a body blank on its way from the magazine to the forming rolls. The body blank is fed by either reciprocating devices or endless feed chains with lugs thereon for moving the body blank, and the magazine and notching devices are necessarily spaced at some distance from the forming rolls.

An object of the present invention is to provide rotating feeding devices for feeding the body blank from the notching mechanism into the feeding rolls whereby the feeding devices may be placed close to the forming rolls and likewise the magazine and notching mechanism close to the feeding devices.

A further object of the invention is to provide a notching mechanism and feeding devices of the above type, wherein the body blanks may be fed from the magazine located directly above both the notching mechanism and the feeding devices into position to be notched and to be engaged by the feeding devices and fed forward to the forming rolls.

A still further object of the invention is to provide an organized mechanism of the above type, wherein the body blank is removed from the magazine by a suction cup, which suction cup positions the blank for notching and also for engagement by the feeding devices.

A still further object of the invention is to provide an organized mechanism of the above type, wherein the body blank is moved in two directions only as it passes from the magazine into the forming rolls, one of which is a downward direction whereby it is placed for notching, and the other of which is a forward direction, whereby it is delivered to the forming rolls.

These and other objects will in part be obvious and will in part be hereinafter more fully disclosed.

In the drawings which show by way of il-

lustration one embodiment of the invention—

Figure 1 is a longitudinal vertical sectional view through the notching and feeding mechanism and also a portion of the body maker;

Fig. 2 is a plan view of the parts shown in Fig. 1;

Fig. 3 is an end view of the parts shown in Fig. 1;

Fig. 4 is a diagrammatic view showing the notching device, the suction cup, the feeding devices and the forming rolls, and their relation to each other;

Fig. 5 is a detail showing the position of the upper feeding device as the blank is moved downward into position to be engaged thereby;

Fig. 6 is a view similar to Fig. 5, showing the blank still on its downward movement, and the feeding device as moving over the blank;

Fig. 7 is a view similar to Fig. 5, but showing the blank as in engagement with the lower rotating feeding device and about to be engaged by the upper segmental rotating feeding device;

Fig. 8 is a view similar to Fig. 5, but showing the blank as gripped between the feeding devices and moving forward to the forming rolls which are also shown diagrammatically in this view;

Fig. 9 is a view showing more or less diagrammatically a side view of the gauges which position the blank for notching and for feeding to the forming rolls;

Fig. 10 is a plan view showing the blank and the position of the gauges relative thereto, and

Fig. 11 is a section through the supporting bracket and bed on the line 11—11 of Fig. 3.

The invention is directed to a feeding and notching mechanism for a body maker, and more particularly to a feeding and notching mechanism for a body maker for making cylindrical can bodies. A type of body maker such as may be used in connection with the improved feeding and notching mechanism is shown in the patent granted I. F. Warne, April 21, 1914, No. 1,094,179. In this type of body maker, a body blank which is a rectangular piece of metal, is fed between

70

100

forming rolls which roll the body blank into a cylinder about a horn. Traveling devices engage and move the formed body through the machine after the edge portions are joined to form a side seam. In the machine referred to, the edges are lapped and soldered, thus forming a lap seam. The blanks are placed in a magazine constructed so that they may be withdrawn one at a time from the lower end thereof. This is accomplished by means of a suction or vacuum cup or cups which have a vertical movement, so as to be brought into engagement with the lowermost blank, and the downward movement of the suction cup will withdraw the blank from the magazine. Directly beneath the magazine at one end thereof, is the notching mechanism, which includes a support for the blank on to which the body blank is placed by the downward movement of the suction cups. The suction cups will place the blank in a predetermined position on the support forming a part of the notching mechanism. The notching mechanism includes a rotating member having projecting cutting devices which, as the member rotates, engages the blank and notches the same. The other end of the body blank is moved by the suction cups into engagement with the feeding devices. The feeding devices include two rotating rolls. The lower roll is a solid roll, while the upper roll is hollow and is cut away to form a segment of a roll. The open space between the ends of the segment is so positioned that when the blank is moved down by the suction cups, the end thereof is moved into this space, and thus it is that the forward end of the segment roll can move over the blank and finally come down into engagement with the blank so as to grip the blank against the lower feed roll and move it forward. These feeding devices are so close to the forming rolls that the blank will be fed into gripping engagement with the forming rolls while it is still positively gripped by the rotating feeding devices.

Referring more in detail to the drawings the invention is shown as applied to a body maker, only a very small portion of which is shown in the drawings. The body maker is provided with a horn 1 indicated diagrammatically in Fig. 1. Directly above this horn are the forming rolls 2, 2. Cooperating with the forming rolls, is the usual curling plate 3. The structure of the head carrying the forming rolls and curling plate is similar to that disclosed in the patent granted J. E. Abrams, February 15, 1910, No. 949,722. A body blank delivered to these forming rolls will be rolled into cylindrical form around the horn 1, and will then be moved endwise through the machine where the side seam is formed. The forming rolls 2, 2 are mounted in a suitable bracket 4 which forms a part of the body maker. Carried by the frame

of the machine is a supporting bed 5 which extends outwardly from the forming rolls 2, 2. Directly above the bed 5 is a magazine for the stacked blanks which are formed into the can bodies. Said magazine includes side plates 6, 6 with an angle bar 7 at each end of each plate. The angle bar 7 is attached to the plate by means of a bolt 8. These angle plates 7 form the end walls of the magazine. They are spaced from each other. The angle bars 7, 7 at the outer end of the magazine are connected by a cross bar 9. Mounted on this cross bar 9 is a cone-shaped plate 10, the inner edge 11 of which passes a short distance underneath the body blank in the magazine, the edge of which is substantially in contact with the inner faces of the angle bars 7. Thus it is that a stack of body blanks may in part be supported by this cone-shaped plate 10. Midway the side plate 6 at one side of the machine, there is a similar cone-shaped plate 12 which extends beneath the body blank and supports the side edge thereof. At the opposite side of the magazine and carried by the other side plate 6, are cone-shaped plates 13 and 14, which likewise project beneath the side edge of the body blank. At the other end of the magazine, there is a tapered plate 15 carried by a cross bar 15^a on which the inner edge portion of the body blank rests. These tapered plates which support the body blanks are so positioned that when a suction cup engages a body blank and pulls down thereon, it will pull the lowermost body blank by the supporting plates, thus releasing the same from the stack. This construction of a magazine whereby the lowermost body blanks are released from the stacked sheets, forms no part of the present invention per se, and other forms of magazines may be used.

The blanks are removed from the magazine by means of one or more suction cups. There are two suction cups shown in the drawings, and indicated at 16, 16. These suction cups are carried by a supporting standard 17, which slides vertically in suitable ways provided therefor. This standard is moved up and down by means of a swinging lever 18 operated by a crank 19 mounted on a shaft 20. The suction cups will engage the body blank and pull the same from the magazine. Two suction cups are preferably used, so that the blank may be firmly gripped and pulled by the supporting plates for the blanks into engagement with the gauges, and through the assistance of the gauges and the suction cups properly placed for notching and for feeding to the forming rolls. At the opposite sides of the magazine and beneath the supporting plates for the stack, are posts which form the side gauges for the blank. These posts are indicated at 200 in the drawings, and as shown, there are two posts for each side of the magazine. The inner face of each

post is slabbed at an angle to the axis of the post as indicated at 201. This is for the purpose of insuring that the blank will, through these tapered or slabbed faces of the posts, be shifted, if necessary, to bring the edges thereof into position so as to pass down alongside of the gauging face of each post. The blanks are cut to a predetermined width, and the gauge posts can be set so that the blank will be gauged thereby and properly positioned transversely of the blank for notching and for feeding forward to the forming rolls after it has been notched. There is a gauge post 202 at the outer end of the blank. This gauge post 202 is provided with an inclined inner face 203 terminating at a shoulder 204. Directly beneath the shoulder 204 is the gauging face 205 of this post. When the blank is drawn down by the suction cups from the magazine, the inner edge of the blank will engage the inclined face 203. These gauge posts are inserted in suitable openings in the bed 5 which are shaped so as to support the same. The suction cups are made of yielding material, and without releasing their grip on the blank, will permit the blank to move endwise slightly, or sidewise slightly, for the proper positioning of the blank relative to the gauges. Thus it is that the blank will move endwise after it engages the inclined face 203. As the suction cup is some distance from the end of the blank, the blank will curve slightly at the end thereof which contacts with this gauge post 202. As soon as the blank passes the shoulder 204, it will straighten out and make contact with the gauging face 205, and this is the active gauging element of this end post. Through these gauges referred to, the blank is properly positioned for notching, and also after it is notched, for engagement by the feeding devices, so that it will be fed forward into the forming rolls. The blank, of course, is in contact with a supporting plate 21 while it is being notched.

The plate 21 is in fact, a part of the notching mechanism which also includes a rotating shaft 22 on which are mounted two notching members 23, 23, one at each corner of the outer end of the blank. This shaft 22 rotates continuously. The member 23 is provided with two cutters 24 and 25 which are diametrically opposed to each other. The plate 21 is shaped so that the cutter as it rotates, will come down on to the body blank and cut or notch the body blank. Of course, the rotating shaft 22 is so timed that the suction cup will lay the blank on the plate 21 before the cutter moves over the top of the blank and down on to the same for notching. At the other end of the magazine, and directly beneath the same, is located the rotating feeding devices for feeding the blank forward into the forming rolls after it is notched. These feeding devices include a

lower feed roll 26 and an upper feed roll 27. These feed rolls are positively rotated by suitable means. The upper feed roll is mounted in journals 27^a which are yieldingly pressed downwardly by suitable springs 27^b so as to yieldingly hold the rolls in contact with each other. The manner of mounting the feed rolls may be widely varied, however, without departing from the spirit of the invention as set forth in the appended claims.

The upper feed roll is formed with a recess 28 which extends for a distance greater than the width of the body blank. This recess, in effect, forms a hollow cylindrical roll. The roll is cut away so as to form a segment, the ends of which are indicated at 29 and 30. The upper feed roll turns in a counterclockwise direction as viewed in the drawings, and the lower feed roll turns in a clockwise direction. These rolls are positively driven and rotate continuously. The body blank is indicated at B in the drawings. The upper feeding roll is so timed that when the body blank is moved down by the suction cup, the end 29 of the upper segment roll is positioned so that the blank may be moved into the recess. The center of the roll lies in a vertical plane inside the extreme inner edge of the body blank. As the body blank continues its downward movement, it moves into the recess 28, as shown in Fig. 6, and the advance end of the segment roll will move over the top of the blank. Thus it is that the blank is brought down directly into contact with the lower roll 26 as shown in Fig. 7. After the blank engages the lower roll, the advancing end of the upper segmental roll is still out of contact with the blank, so that the blank will remain on the lower roll an appreciable time before the upper segmental roll makes contact therewith. It is during this interval of time that the notching takes place, and after the blank is notched, then it is in condition to move forward into the forming rolls. In Fig. 8, the upper segmental roll is shown as having moved into engagement with the body blank so that the body blank is gripped between the rolls and is being moved forward to the forming rolls. There is a sufficient length of feeding surface on the upper segmental roll so as to carry the blank clear into the forming rolls.

From the above, it will be apparent that a notching mechanism has been provided wherein a body blank may be fed from the magazine directly downward and placed for notching in the notching mechanism. It will also be noted that a feeding mechanism has been provided whereby the blank when it is positioned for notching, is positioned also for engagement by the feeding mechanism, and as soon as it is notched, the blank will be at once engaged by a continuously rotating feeding mechanism and move forward into the feeding rolls. The blank on its way from

the magazine to the forming rolls moves only in two directions, first, a downward direction and then a forward direction. Furthermore, the feeding devices may be placed very close to the forming rolls so that the interval of time between the removal of a body blank from the magazine and the delivering of the same to the forming rolls is very short. This provides a notching and feeding mechanism 10 wherein the blanks may be delivered very rapidly to the body maker, and the body maker operated at very high speed. The notching and feeding mechanism may be used in conjunction with either a lap seam body maker or a lap and lock seam body maker. It may be used in conjunction with a body maker which rolls a cylindrical body about a horn below the forming rolls, or which rolls a cylindrical can body about a horn which is 20 above the forming rolls. The invention is directed to the handling of the blank between the magazine and the forming rolls. It will be understood from certain aspects of the invention, the notching mechanism 25 shown and described may be used in conjunction with other types of feeding devices, and also that the feeding devices may be used in conjunction with other types of notching devices. It is further obvious that 30 minor changes in the details of construction and the arrangement of the parts may be made without departing from the spirit of the invention as set forth in the appended claims.

35 Having thus described the invention, what we claim as new and desire to secure by Letters Patent is—

1. In a body maker, the combination of forming rolls, notching mechanism, means 40 for feeding the body blanks to the notching mechanism, and rotating feeding devices disposed between the forming rolls and the notching mechanism for engaging and moving a blank from the notching mechanism 45 into the forming rolls.
2. In a body maker, the combination of forming rolls, a magazine for the body blanks, a notching mechanism, means for delivering the blanks from the magazine to 50 the notching mechanism, and rotating feeding devices disposed between the forming rolls and the notching mechanism for engaging and moving the blanks from the notching mechanism into the forming rolls.
- 55 3. In a body maker, the combination of forming rolls, a notching mechanism, a magazine for body blanks located above said notching mechanism, means for feeding the blanks from the magazine to the notching mechanism by a downward movement of the blank, and means for feeding the blank from the notching mechanism in an endwise direction into the forming rolls.
- 60 4. In a body maker, the combination of forming rolls, a notching mechanism, a mag-

azine for body blanks located above said notching mechanism, means for feeding the blanks from the magazine to the notching mechanism by a downward movement of the blank, and means for feeding the blank from the notching mechanism in an endwise direction into the forming rolls, said means for feeding the blanks from the magazine including a suction cup for holding and placing the blanks in a predetermined position in the notching mechanism. 70

5. In a body maker, the combination of forming rolls, a notching mechanism, rotating feeding devices disposed between the forming rolls and the notching mechanism for engaging and moving the blanks from the notching mechanism into the forming rolls, a magazine, and means for feeding a body blank from the magazine to the notching mechanism and rotating feeding devices. 80

6. In a body maker, the combination of forming rolls, rotating feeding devices located close to said forming rolls, a magazine for sheet metal blanks located above the feeding devices, said feeding devices including 90 an upper segmental feeding roll having a central recess, and means for feeding the blank from the magazine past the end of the segment of the roll and into contact with the lower feeding device, whereby the segmental roll as it continues its rotation, will grip the blank against the lower feeding device and move the same forward into the forming rolls. 95

7. In a body maker, the combination of forming rolls, a notching mechanism including rotating notching members, rotating feeding rolls for engaging and feeding the blank from the notching mechanism into the forming rolls, a magazine above the notching mechanism and feeding rolls, and means for feeding a body blank from the magazine simultaneously into proper position to be notched and to be engaged by the feeding rolls for feeding the same forward after it 10 is notched. 11

8. In a body maker, the combination of forming rolls, a notching mechanism including rotating cutters for notching the body blank, a magazine for the body blanks located above said notching mechanism, means for feeding the blanks from the magazine to the notching mechanism by a downward movement of the blank, and means for feeding the blank from the notching mechanism 12 into the forming rolls. 11

9. In a body maker, the combination of forming rolls, a notching mechanism including rotating cutters for notching the body blank, a magazine for body blanks located above said notching mechanism, means for feeding the blanks from the magazine to the notching mechanism by a downward movement of the blank, and rotating feeding devices for engaging and feeding the blank 130

from the notching mechanism into the forming rolls.

10. In a body maker, the combination of forming rolls, a notching mechanism including rotating cutters for notching the body blank, gauging devices for positioning the blanks for notching, and means for feeding the blank after it is notched to the forming rolls.

11. In a body maker, the combination of forming rolls, a notching mechanism including rotating cutters for notching the body blank, gauging devices for positioning the blanks for notching, and rotating feeding devices disposed between the forming rolls and the notching mechanism for engaging and moving the blanks from the notching mechanism into the forming rolls.

12. In a body maker, the combination of forming rolls, a notching mechanism, rotating feeding rolls independent of the forming rolls for engaging and feeding the blank from the notching mechanism into the forming rolls, a magazine above the notching mechanism and feeding rolls, and means for feeding a blank from the magazine simultaneously into proper position to be notched and to be engaged by the feeding rolls for feeding the same forward after it is notched to the forming rolls.

13. In a body maker, the combination of forming rolls, a supporting bed along which the blanks may be fed to the forming rolls, a magazine above said supporting bed, rotating feeding rolls for engaging and feeding the blanks into the forming rolls, and means for feeding the blanks from the magazine onto the bed in position to be engaged by the feeding rolls for feeding the same forward into the forming rolls.

In testimony whereof, we affix our signatures.

JAMES EDWARD BRATT.
CHARLES HUNTER BOYD.
